UNITED STATES PATENT OFFICE

2,374,448

TAILSTOCK FOR MILLING MACHINES

Erick Moen, Detroit, Mich.

Application March 11, 1943, Serial No. 478,778

3 Claims. (Cl. 90—23)

My invention relates to the tail stock covered in my Patent No. 2,242,978, dated May 20, 1941, and also to a center pin installation for such tail stock covered in my Patent No. 2,265,568, dated December 9, 1941, and my main object is to provide a tail stock containing improvements over the patented structures.

Another object of my invention is to provide a number of features which make for the better construction of the tail stock, the improved control of its adjustment, and greater facility in the installation and handling of the tail stock.

With the above objects in view and any others which may suggest themselves from the description to follow, a better understanding of the invention may be had by reference to the accompanying drawings, in which—

Fig. 1 is a side elevation of the improved tail stock, following the lines of Fig. 1 in either patent above referred to;

Fig. 2 is a longitudinal section similar in its lower and right-hand portions to Fig. 2 in the earlier patent, and in its upper left-hand portion to Fig. 2 in the later patent;

Fig. 3 is a top plan view of the tail stock similar to Fig. 5 in the earlier patent;

Fig. 4 is a plan section similar to Fig. 6 in the earlier patent;

Fig. 5 is a rear view similar to Fig. 7 in the earlier patent;

Fig. 6 is a rear section similar to Fig. 3 in the earlier patent;

Fig. 7 is a section on the line 7—7 of Fig. 1; and

Fig. 8 is a front view of the center pin installation similar to Fig. 4 in the later patent.

In a general sense, the improved tail stock embodies the construction of the earlier patent, and the center pin installation of the later one. Thus, reference to parts in these structures will be by means of numerals employed in the patents referred to. On the other hand, reference to new features will be made by means of other numerals.

Initially, one change is noted in the construction of the base 10. Whereas the same is made low at the rear only in the earlier patent, the numeral 90 in Fig. 1 shows that the frontal part of the improved base is also made low, to facilitate the application of short bolts to secure the base to the milling machine bed.

The second improvement resides in a change of the form and application of the bearing arch 20 in the earlier patent. While such arch appears rounded and is secured by bolts 22, the

improved structure shows the counterpart of the arch 20 to be a keystone-shaped bearing standard 91 which is made separate from the base and welded to the same on a line 92, as suggested in Fig. 6, or made in one piece with the base 10. The bearing standard is therefore more rigid; and the tapping of holes and use of fastening bolts is eliminated.

A further improvement resides in the locking 10 of the feed screw 17 of the earlier patent. Whereas this was done by the provision of a collar 25 on the inner side of the screw shank and a receptacle 23 rising from the base 10, a more compact form of lock is employed in the improved 15 structure, as illustrated in Figs. 4 and 6. Here it is seen that the shank of the feed screw 17 is annularly grooved at 93. A bolt 94 is screwed downwardly into the bearing standard 91 to seat in one side of the stem groove 93. Thus, the stem 20 is locked from longitudinal motion; and the movement of the slide 14 can be brought much closer to the bearing standard than before. Incidentally, the head of the feed screw 17 is now square, as indicated at 95, for the application 25 of a common wrench when the feed screw is to be operated. Also, the slide 14 is recessed in front, as indicated at 95a, to straddle the bearing standard when approaching the limit of its retraction and gain added movement.

Another improvement deals with the bolt 53 employed in the earlier patent to lock the slide 14 at any point in its movement. Provision is made 30 in the new embodiment to lend the bolt a better hold and reduce the wear incident thereto. Thus,

Figs. 4 and 6 show the application of a cold 35 rolled steel plate 96 between the slide 14 and the base 10 at one side of the tail stock. The outer portion of the plate is secured to the base by means of a bolt 97 and lock washer 98, while the inner portion of the plate assumes a position under the lower end of the bolt 53.

Such end is concaved as indicated at 99 to give it a sharp 40 marginal edge. Thus, when the bolt is screwed down, its edge secures a sharp or cutting hold on the plate 96, such hold receiving a minimum amount of wear because of the hardness of the plate.

It follows, therefore, that the plate may be used for a long time before it becomes so scored or worn that it will no longer offer a good hold 45 for the bolt. In such event, it is an easy matter to remove the plate and to replace the same with a new one at nominal cost. It is preferable to employ a lock washer 100 under the head of the bolt 53.

It is also noted that the side keys 48 of the 50

It is also noted that the side keys 48 of the

block 30 in the earlier patent are now replaced by two sets of side keys 101 occurring at the ends of the block, as clearly shown in Figs. 3 and 4. A double bearing is thus secured by the block. Incidentally, the vertical bore in the block is moved back from the center in the new embodiment, as noted in Fig. 2. This allows more stock in the front of the block to form a bearing or support for the center pin installation.

Another change occurs in the transmission of motion from the spindle 41 to the pin 46. Whereas the spindle of the earlier patent has a worm thread 42 in mesh with a gear 45 on the pin 46, the said thread and gear are now replaced by a pair of meshing spiral gears 102 which eliminate the need of threading the spindle 41. The latter is reduced in front as indicated at 103 to find a bearing in the end wall 35, as before, but to the rear of the gear 102 a reduction 104 of the spindle receives a spacer sleeve 105. The knob 48 is secured to the rear end of the spindle by a cross-pin 105a; and the knob is now formed with a square head 106 for the application of an ordinary wrench when the spindle 41 is to be operated.

The mounting of the center pin now employs the corresponding construction of the later patent, and the structure of the tail stock is simplified for the adjustment of the center pin shaft 57. As noted in Fig. 2, the said shaft is not formed with a threaded extension, but is bored and tapped with a horizontal cavity from the rear to receive a screw 107 forming the frontal extension of a shank 108 having a knob 109 at its rear end. The shank 108 is freely disposed in the tail stock, but means are provided to lock the shank against longitudinal motion as well as to check it against rotation when it has once been adjusted. Thus, Fig. 2 shows that the shank 108 is made with an annular groove 110. The rear extension 64 of the tail stock receives a tapered pin 111 from the bottom, as shown in Fig. 7, the pin seating in one side of the groove 110 and continuing upwardly in the form of a screw 112 rising from the extension 64. This screw receives a wing nut 113. Ordinarily, the pin 111 forms a lock to fix the shank 108 against longitudinal travel. However, after the knob 110 has been rotated to adjust the center pin longitudinally, the tightening of the wing nut 113 draws upwardly on the pin 111 to wedge it in the side of the shank 108, also locking the same against rotary motion. Figs. 2 and 5 show that a crank handle 114 is applied to the back of the knob 109 by means of a pair of screws 115 in the event that it is difficult to turn the knob 109. However, the crank handle may be removed or dispensed with in case this difficulty does not occur.

It will be evident from the above description that the salient features of the tail stock remain as before, but that they carry improvements which make for greater stability or strength of the tail stock, easier operation of its working parts, smoother adjusting action and greater simplicity.

I claim:

1. In a milling machine tail stock, a top bearing, a center pin longitudinally adjustable in the bearing and having a rear portion horizontally tapped to serve as a traveling nut, a screw rotatable in the latter, a shank for the screw in the rear end of the bearing, a head carried by the shank rearwardly of the bearing, and means co-operative with the shank to lock the same against longitudinal and rotary motion, said means comprising an annular groove in the shank, a locking pin disposed in the bearing alongside the shank and seating tangentially in said groove, said locking pin being tapered, and means to draw on the locking pin to wedge it tightly in the groove.
2. In a milling machine tail stock, a top bearing, a center pin longitudinally adjustable in the bearing and having a rear portion horizontally tapped to serve as a traveling nut, a screw rotatable in the latter, a shank for the screw in the rear end of the bearing, a head carried by the shank rearwardly of the bearing, and means co-operative with the shank to lock the same against longitudinal and rotary motion, said means comprising an annular groove of part-circular cross-section in the shank, a locking pin disposed in the bearing alongside the shank and seating tangentially in said groove, said locking pin being conically tapered, and means to draw on the locking pin to wedge it tightly in the groove.
3. In a milling machine tail stock, a top bearing, a center pin longitudinally adjustable in the bearing and having a rear portion horizontally tapped to serve as a traveling nut, a screw rotatable in the latter, a shank for the screw in the rear end of the bearing, a head carried by the shank rearwardly of the bearing, and means co-operative with the shank to lock the same against longitudinal and rotary motion, said means comprising an annular groove in the shank, a locking pin disposed in the bearing alongside the shank and seating tangentially in said groove, said locking pin being tapered and with a screw projecting from its smaller end, and a wing nut applied to the locking-pin screw and operable to wedge it tightly in the groove.

ERICK MOEN.
